WARDROBE STRUCTURE

Richard T. McKnew, Washington, D. C.

Application May 4, 1931, Serial No. 535,045

12 Claims. (Cl. 20—19)

This invention relates to wardrobe structures such as are used in the present-day school rooms, and has particular reference to the manner in which the fronts of such wardrobes are constructed and especially the arrangement of the doors of such fronts and the way in which they are hung and operated.

In wardrobes of this general type, it is customary to so arrange and hang the doors, which for the most part form the wardrobe fronts, that they may be opened to a position substantially at right angles to the back of the wardrobe and within the space of the wardrobe, thus taking up practically no more space when open than when closed.

In most of the wardrobes of this type with which I am familiar, the doors are hung upon pivotal supports in the form of swinging arms carried upon the floors and ceilings of the wardrobes, and in such positions upon the floors that they obstruct the floor space and are not only a hindrance to cleaning the floors, thus tending to make the wardrobes unsanitary, but are apt to be tripped over, and hence are an inconvenience in the use of the wardrobes and a menace to the safety of those using them.

Moreover, the hardware necessary to hang the doors in this prevalent manner is expensive, laborious and time-consuming to set up, does not lend itself readily to the proper alignment of the doors, and requires many adjustments to insure the proper hanging and functioning of the doors.

One of the objects of my invention is to provide a wardrobe front including, preferably, six doors, four of which are supported upon mullions which tend to separate the wardrobe into three intercommunicating compartments, and the other two of which are separately supported adjacent to the end walls of the wardrobe alcove.

Another object of my invention is to provide a means of hanging the doors of wardrobes of the type referred to, whereby all members which are mounted upon the floor and obstruct the floor space of the wardrobes are eliminated.

Still another object is to provide door hardware of such a nature that the proper hanging and adjustment of the doors is facilitated.

A further object is to provide fastening means for the doors, whereby the doors may be latched in closed position by engagement of the latches with the mullions. This method of latching does away with fastening means on the doors which normally project from the top edges thereof for engagement with keepers in the top framing of the wardrobe opening, and thus makes it possible,

if desired, to position the doors, when opened, entirely within the wardrobe alcove without any projection of them into the room.

A still further object is to provide door hardware which is relatively cheap and requires little labor in its application on the job.

Furthermore, in my hardware, I do not use any rollers, slides, slideways or other similar relatively moving parts which, as at present employed, tend to noisy and stiff opening and closing of the doors.

With these and other objects in view, the invention consists in means for hanging the doors of enclosures, particularly of alcove wardrobes, whereby they may operate in a manner which has become standard practice, but without obstructing the wardrobe space, including a mullion member, a hinge member and arms for the door adjacent to such mullion, and a guide link for directing the swinging movement of the door, and in various details of construction and arrangement, all as will be explained hereinafter more fully and finally claimed.

In the accompanying drawings illustrating the invention, in the several figures of which like parts are similarly designated, Figure 1 is a front elevation of a six-door wardrobe, the doors of which are arranged and hung in accordance with my invention, Fig. 2 is an enlarged fragmentary sectional plan view showing the doors in full lines in closed position and in broken lines in open position. Fig. 3 is a fragmentary sectional detail taken on line 3—3, Fig. 2, of the pivotal connections carried at the top of each door and to which one hinge arm and the guide link are connected. Fig. 4 is a fragmentary sectional plan view, similar to Fig. 2, but showing progressive positions of the doors during their opening movement. Fig. 5 is a sectional elevation taken on line 5—5 of Fig. 2. Fig. 6 is an enlarged detail view taken on line 6—6 of Fig. 5. Fig. 7 is a fragmentary elevation of the parts shown in Fig. 6. Figs. 8 and 9 illustrate, on a greatly enlarged scale, two types of latch mechanism for the doors. Fig. 10 is a view similar to Fig. 5 but illustrating a modified arrangement of hardware. Fig. 11 is a fragmentary rear elevation showing the hardware of Fig. 10. Fig. 12 is a section taken on line 12—12 of Fig. 10.

Although the invention is susceptible of use with various door installations, it is particularly adapted for school wardrobes of the type referred to, and the following description will relate to such an installation, it being understood that it is not intended to thereby limit the invention.

In accordance with the customary practice, an alcove 1 is formed in a wall of the school room, and the back wall 2 of this alcove may be provided with the customary shelves and hooks (not shown) to receive the garments and other belongings of the students.

The alcove 1 is provided with a closure or front comprising, in the installation shown in Fig. 1, six doors, *a*, *b*, *c*, *d*, *e* and *f*, the doors *b* and *c*, 10 and *d* and *e* being arranged in pairs. These six doors divide the wardrobe into three intercommunicating compartments defined by the mullions 3 and 4. The doors are preferably provided with blackboards 5 and chalk rails 6, and the mullions 15 3 and 4 and end trim pieces 7 and 8 carry conveniently arranged eraser holders 9. As will be seen, the doors do not extend to the floor line 10 but leave below them a space which provides for free circulation of air within the wardrobe.

20 Referring to the form of the invention illustrated in Figs. 2 to 9, inclusive, it will be seen that in line with each of the mullions 3 and 4 I erect a metallic mullion member 11 fastened at its lower end to the floor 10 and at its upper end to a string piece or girder 12 by means of similar angle members 13 and 14, respectively. Each of these angle members, as shown in detail in Figs. 6 and 7, is provided in its leg which engages the floor 10 or girder 12 with an enlarged central opening 15 25 adapted to receive a screw 16 of less diameter than the opening 15. The head of this screw engages a washer 17 which spans the opening 15. The other leg of each angle member is provided with a plurality of slots 18 to receive screws 19 30 by means of which the angle member may be secured to the mullion member 11 and provide for vertical adjustment thereof. Lock-washers 20 may be used with the screws 19, if desired.

35 The mullion members 11 have welded or otherwise preferably rigidly attached to them similar top and bottom pivot brackets 21 each of which is provided with two sockets in which are pivoted, in substantial parallelism, hinge members or swivel bars 22, preferably of tubular form, carrying hinge arms 23 rigid with them and having free ends pivoted in bearing members 24 adjustably 40 attached by slots 25 and screws 26 (see Fig. 3) adjacent to the top and bottom edges of the doors *b*, *c* and *d*, *e* to support the doors upon the arms 45 in such arrangement relatively to the vertical centers of the doors as to accomplish the desired swinging action of the doors.

50 The mullions 7 and 8 are provided with similarly arranged and adjusted mullion members 27 carrying single socketed pivot brackets 28 in which are pivoted hinge members or swivel bars 22 for the doors *a* and *f* which are carried by hinge arms 23 and bearing members 24 like those used for the doors *b*, *c*, *d* and *e*.

55 60 When the several doors have been adjusted for vertical alignment by means of the shiftability of the angle members 13 and 14 relatively to the floor 10 and girder 12, due to the relative diameters of the screws 16 and openings 15, and with them of the mullion members 11 and the hinge parts carried thereby, the angle members may be fixed in position by a plurality of screws 29. Any further lateral vertical adjustment of the doors may be made by means of the screw and slot arrangement 25, 26 of the bearing members 24 and then these bearing members may be fixedly attached to the doors by screws 30.

65 70 The doors may be horizontally aligned by means of the slot and screw connection 18, 19 between the mullion members 11 and 27 and their

angle members 13; or shims or washers may be interposed between the hinge arms 23 and their bearing members 24.

75 When the mullion members 11 and 27 are properly adjusted and fixed, the mullions or trim pieces 3, 4, 7 and 8 may be set up by nailing them to the floor 10 and to a trim strip 34, or in any other suitable manner.

80 As hereinbefore mentioned, it is standard practice to have the doors of wardrobes of this type swing from the closed position, as shown in full lines, Fig. 2, to the open position as shown in broken lines, Fig. 2, so that when open they do not project into the room sufficiently to be a nuisance but, on the contrary, lie almost wholly within the wardrobe. The hinge members 23 are so attached to the doors relatively to their vertical centers as to swing the butt edges of the doors well within the wardrobe space, but to insure their movement to the desired open position shown in Fig. 2, 20 it is desirable to provide means for guiding them to this position when they are swung open.

85 As a simple and effective means for this purpose, I provide guide links 32 having fixed pivots 33 upon cross-braces 34 adjustably carried upon angles 35 by slot and bolt connections 36, 37. The opposite ends of these links are connected to the doors by bearing members 38 adjustable in a manner similar to the members 24 (see Fig. 3).

90 Referring to Figs. 2 and 4, and taking the door *b* as an example, the swinging of the door from closed to open position is accomplished as follows:—The knob 39 is grasped and turned to release the latch (hereinafter described) and an outward pull is exerted. This pull will cause the door to take a double pivotal action on its hinge arms 23 and about the pivotal points defined by the bars 22 and members 24 guided by the guide link 32, so that its butt edge will be turned into the wardrobe space, substantially as shown in full lines in Fig. 4. As the pull is continued, this double pivotal action of the door will progress until the door assumes the position shown in broken lines in Fig. 4, and thereafter, as the pull continues, will assume the position shown in 45 broken lines in Fig. 2, the fully opened position.

95 The doors are caused to stop when they reach this fully opened position by means of stop members 43, see particularly Fig. 4, which butt against bumpers 44, preferably of rubber or some other 50 more or less resilient material, carried by a longitudinal member 42 mounted on brackets 43 affixed to the end walls of the alcove, with respect to which brackets the longitudinal member 42 is adjustable by means of slot and bolt connections as indicated at 44, 45. In order that the mullions 3 and 4, and trim pieces 7 and 8 may not be marred by having the chalk rails 6 of the doors strike against them, I provide rubber or other buttons 46 upon the stiles and in line with the chalk rails, as shown.

100 Obviously, it is desirable to have some sort of latch mechanism for holding the doors in closed position, and I have devised a novel arrangement whereby the doors may be latched to their adjacent mullions. Two forms of such latch mechanism are illustrated in Figs. 8 and 9, respectively. In Fig. 8, I show an arrangement where the latches are assembled at the back of the door, and in Fig. 9 I show a similar arrangement, but with the latch members assembled at the front of the door.

105 In both forms shown, the latch comprises a latch member 47 and a keeper 48. The latch member 47 is normally forced into engagement 75

with the keeper by means of a spring 49 and is withdrawn by means of a flexible link 50 connected with the knob 39 of the door and operating to withdraw the latch member from the keeper when the knob is turned. The latch member will automatically snap into its keeper, under the influence of spring 49, upon closing of the door, as is customary. Although I have shown the knobs as arranged at the meeting edges of the doors, in the conventional manner, I may mount them at the edges adjacent to the mullions, in which latter case the links 50 may be dispensed with and the latches be of the ordinary mortised form.

In Fig. 8, the keeper is in the form of a bent plate having two offstanding parts 51 in which are formed openings 52 into which openings the latch members may project. This keeper plate 48 is fixed upon the stile or mullion member 11 by means of bolts 53, and may be adjusted relatively to the stile 3 so as to insure proper alignment of the doors with respect thereto when closed by means of suitable shims 54 interposed between the member 11 and the plate 48.

In Fig. 9, the keeper is a flat plate having its ends offstanding sufficiently to be engaged by the latch members 47 of the adjacent doors. This plate 48 is carried on bolts 55 mounted on the stile member 11 and is adjustable relatively to the member 11 and the stile 3 by means of nuts 56.

In the modification illustrated in Figs. 10 to 12 inclusive, I have disclosed hardware to take the place of that shown in Figs. 2 to 7 inclusive, and which, although it has the same functional characteristics, so far as operation of the doors is concerned, as that already described, comprises fewer parts, is less expensive, and is somewhat easier to set upon the job.

In this modified form of hardware, I dispense with the members 11, 13 and 14, and the parts used therewith to adjust them, and mount the hinge members or swivel bars 22 in step pieces 57 and bearing brackets 58 arranged upon the floor 10 and against the stringer 12 respectively. The stringer 12 or its facing piece 12' may be notched, as indicated at 59, to receive the bearing brackets 58 and prevent their lateral movement, to thus assist the screws 60 in holding them in position. The step pieces 57 are provided with sockets 61 which may be bushed or not, as desired, to receive the lower ends of the swivel bars 22, and the upper ends of these bars extend through openings 62 in the brackets 58 and into openings 63 provided in the stringers 12 or in the facing pieces 12' applied thereto. The step pieces 57 are properly adjusted for vertical alignment of the doors by adjusting them upon the floor 10 with the swivel bars 22 stepped in them and in engagement with the brackets 58. When proper vertical adjustment is obtained the step pieces may have shims (not shown) slipped under them to adjust the doors horizontally, if necessary, and are then secured to the floor by means of a plurality of screws 64. When the mullions, such as 3, are put in place and the trim including the strip 31 assembled, the step pieces may be screwed to the mullions, as shown at 65, and the brackets 58 may be secured to the strip 31 by screws, as indicated at 66. Obviously, if desired, sufficient play may be provided for vertical movement of the swivel bars 22 to permit them to be removed from the step pieces 57 and brackets 58.

The hinge arms 23 and their connection 24 with

the doors may be, and preferably is, the same as that already described.

The cross braces 34 are used as before, but instead of using the type of guide links 32 hereinbefore described, I substitute therefor bent rods 67 having one of their ends screwthreaded, as indicated at 68, and screwed into blocks 69 welded or otherwise affixed to the cross braces 34. The other ends of these bent rods 67 are seated in bearing sockets 70 in adjustable members 71 having the same function as the members 38, hereinbefore described.

It will be seen that this modified form of hardware is much simpler than that previously described, and although it does not include the elements for adjustment of the doors which form a part of the other type of hardware, it can be adjusted readily on the job so as to properly position the doors as desired.

No matter whether the type of hardware disclosed in Figs. 2 to 7 or the type disclosed in Figs. 10 to 12 is employed in hanging the doors of the wardrobe, it will be apparent that there are no members of the hardware arranged upon the floor of the wardrobe in such positions as to obstruct the floor space within the wardrobe. On the contrary, the doors are, in effect, hung from the mullions, and all of the hinge members therefor are located directly behind the mullions. Thus I provide clear floor space within the wardrobe and free space above the floor from end to end of the wardrobe throughout its several compartments.

By making the swivel bars or hinge members 22 and the hinge arms 23 as integral structures, it will be apparent that I forestall the possibility of having them incorrectly assembled relatively to the doors when installed upon the job. This feature, moreover, makes the door supports relatively rigid and lessens the possibility of sagging and misalignment of the doors occurring after continued operation.

I am aware that I am not the first to hang doors by means of swivel bars having rigid hinge arms on which the doors are pivotally supported at top and bottom and to guide such doors in their swinging movement. This is disclosed broadly in the British patent of George Napier, No. 22,283 of 1894. But I do believe that I am the first to develop this construction for wardrobe use, and to so mount the hinge members for the doors that two doors may be supported from behind a single dividing mullion, and to provide a guide link for guiding each door, the arrangement of this hardware being such that the usable floor space of the wardrobe is not obstructed, and the hardware itself, particularly the hinge members, is out of sight behind the mullions.

Moreover, the features of adjustability of the hardware, the supporting of the doors in pairs, and the manner of latching the doors to the mullions, are new so far as I am aware, as are other details of construction hereinafter claimed.

Various changes other than and in addition to those specifically mentioned are contemplated as within the spirit of the invention and the scope of the following claims.

What I claim is:—

1. A front for wardrobes and the like, including a plurality of doors arranged in pairs, hinge means for said doors supported by adjacent portions of the wardrobe structure and including pivotal supports comprising swivel bars and arms carried thereby, said doors being pivotally supported relatively to said bars and arms, and pivotal mountings for said hinge means, said pivotal mountings

- when the doors are open lying behind and substantially concealed by the doors and remote from the usable floor space of the wardrobe lying between the open pairs of doors.
5. A front for wardrobes and the like, including a plurality of doors arranged in pairs, a mullion interposed between each pair of doors, hinge means including a swivel bar and arms for one door of each pair of doors, said doors being pivotally supported relatively to said bars and arms, said hinge means carried by pivotal mountings supported by adjacent portions of the wardrobe structure and arranged behind the respective mullion, and said pivotal mountings being substantially concealed and remote from the usable floor space of said wardrobe as defined by the doors when open.
10. A front for wardrobes and the like, including a plurality of doors arranged in pairs, a mullion interposed between each pair of doors, hinge means for one door of each pair of doors including a swivel bar and arms for each of said doors, said doors being pivotally supported relatively to said bars and arms, and a joint pivotal mounting for both of said bars arranged behind the respective mullion, said pivotal mountings being substantially concealed and located remote from the usable floor space of said wardrobe as defined by the doors when open.
15. A front for wardrobes and the like, including a plurality of doors arranged in pairs, a mullion interposed between each pair of doors, hinge means for one door of each pair of doors including a swivel bar for each of said doors and arms connected with said swivel bars, said doors pivotally carried relatively to said bars and arms, and a joint pivotal mounting for both of said bars arranged behind the respective mullion, said pivotal mountings being substantially concealed and located remote from the usable floor space of said wardrobe as defined by the doors when open, and means for guiding the opening and closing movement of said doors upon their hinge means.
20. A front for wardrobes and the like, including a plurality of doors arranged in pairs, a mullion interposed between each pair of doors, hinge means for one door of each pair of doors including a swivel bar for each of said doors and arms connected with said bars, said doors pivotally carried relatively to said bars and arms, and a joint pivotal mounting for both of said bars arranged behind the respective mullion, said pivotal mountings being substantially concealed by the mullions and located remote from the usable floor space of said wardrobe as defined by the doors when open, and means for latching one door of each pair of doors to each of said mullions when said doors are in closed position.
25. A front for wardrobes and the like, including a plurality of doors arranged in pairs, a mullion interposed between each pair of doors, hinge means for one door of each pair of doors including swivel bars and arms carried thereby, and pivot members for said bars abutted against and concealed by said mullions behind the same, whereby said doors are supported for swinging action relatively to said mullions and the usable floor space of said wardrobe as defined by said doors when open is unencumbered.
30. In a wardrobe or the like, a door, hinge means for said door including a pivoted swivel bar provided with a pair of hinge arms, said door pivotally carried relatively to said bar and arms and swingable from closed to open position therewith and vice versa, a pivotal mounting for said hinge means supported by the wardrobe structure remote from the usable floor space as defined by the door when open, and a guide link having a relatively fixed pivot at one end and pivoted to said door at its other end, said link adapted to guide said door during the opening and closing movements.
35. In a wardrobe or the like, a door, hinge means for said door including a pivoted swivel bar carrying in fixed relation thereto a pair of spaced door supporting hinge arms, said door pivotally carried by said arms and swingable with said swivel bar and relatively to said arms, a pivotal mounting for said swivel bar supported by the wardrobe structure remote from the usable floor space as defined by the door when open, and a guide link having a relatively fixed pivot at one end and pivoted to said door at its other end, said door swingable from closed position to an open position substantially normal thereto, and said guide link adapted to guide said door from closed to open position and vice versa.
40. In a wardrobe or the like, a door, hinge means therefor comprising, in combination, a pivoted swivel bar carrying a pair of door supporting hinge arms, a door pivotally carried by said arms and swingable with said swivel bar and relatively to said arms, a pivotal mounting for said swivel bar supported by the wardrobe structure remote from the usable floor space and defined by the door when open, means for adjusting the pivotal connection of said arms with said door, a guide link having a relatively fixed pivot at one end and pivoted to said door at its other end, and means for adjusting the position of said fixed pivot, said door swingable from closed position to an open position substantially normal thereto, and said guide link adapted to guide said door from closed to open position and vice versa.
45. In a wardrobe or the like, the combination with two doors and a mullion interposed between the same, of two swivel bars carrying hinge arms, said doors supported by said bars and arms and pivotally carried relatively to said arms, means arranged adjacent to and concealed by said mullion for pivotally mounting both of said swivel bars and for adjusting same simultaneously, said pivotal mounting means due to their arrangement being located remote from the usable floor space as defined by the doors when open, said doors adapted to swing on said swivel bars and relatively to said arms, and a guide link for each door, said guide links pivoted to said doors and to relatively fixed supports, said doors being guided by said links from closed to open position and vice versa as they are swung on said swivel bars and relatively to said arms.
50. In a wardrobe or the like, a mullion member, a pair of pivot brackets carried by said member adjacent to its top and bottom, a swivel bar mounted in said brackets and rotatable therein upon its longitudinal axis, a pair of hinge arms carried by said bar adjacent to its ends, a door supported upon said arms in pivotal relation thereto, said door being swingable from closed to open position upon said swivel bar and relatively to said hinge arms, and means pivoted to said door and to a relatively fixed support for guiding such swinging movement.
55. In a wardrobe or the like, a mullion member, a pair of pivot brackets carried by said member adjacent to its top and bottom, a swivel bar mounted in said brackets and rotatable therein

upon its longitudinal axis, a pair of hinge arms carried by said bar adjacent to its ends, a door supported upon said arms in pivotal relation thereto, said door being swingable from closed

5 to open position upon said swivel bar and relatively to said hinge arms, means for adjustably

supporting said mullion member relatively to the floor and ceiling of said wardrobe whereby said door may be vertically adjusted, and means for guiding such swinging movement.

5

RICHARD T. MCKNEW.
